UNITED STATES PATENT OFFICE.

CHARLES EDWARD HAND, OF DUNDAS, ONTARIO, CANADA.

COMPASSES OR DIVIDERS.

No. 920,461.

Specification of Letters Patent.

Patented May 4, 1909.

Application filed May 21, 1908. Serial No. 434,016.

To all whom it may concern:

Be it known that I, CHARLES EDWARD HAND, a subject of the King of Great Britain, and resident of Dundas, in the county of 5 Wentworth and Province of Ontario, Canada, have invented new and useful Improvements in Compasses or Dividers, of which the following is a specification.

My invention relates to improvements in 10 compasses, or dividers, in which pivotally connected legs are provided with pivotally connected marking elements and link members eccentrically operating in the legs and connected to said marking elements that at 15 the adjustment of the compass, the marking elements shall be parallel with each other, together with the centrally located upper handle.

The objects of my invention are first, to 20 provide a compass having substantially parallel marking elements; second, to provide a compass having a handle, which shall be substantially parallel with the marking elements at the adjustment of the compass; third, to 25 provide means whereby one said compass point, or marking element, may be minutely, and independently adjusted, fourth, to provide means whereby the lower connections of 30 the link members shall receive proper spring tension to retain the same in operative position with the movable compass marking element mechanism. I attain these objects by the mechanism illustrated in the accompanying drawing in which:—

Figure 1 is an elevation of the compass partially widened out. Fig. 2 is an elevation of the same, partially contracted, the upper tightening thumb screw, together with the compass marking elements, or points, being 40 removed. Fig. 3 is a detail elevation of the detached centrally located handle. Fig. 4 is a section of a leg through the horizontal broken line 2, 2, in Figs. 1 and 2 of the drawing. Fig. 5 is an elevation of the detached 45 left-hand link member of the compass. Fig. 6 is an elevation of the detached right-hand link member of the compass. Fig. 7 is an elevation of the detached left-hand leg of the compass, as viewed from the inner side thereof. Fig. 8 is an elevation of the detached 50 right-hand leg of the compass as viewed from the inner side thereof. Fig. 9 is an enlarged 55 sectional elevation of the upper part of the compass through the central broken vertical line 3, 3, of Fig. 1, of the drawing, and as viewed from the right-hand side thereof, the

lower parts of the compass being broken away.

Similar characters refer to similar parts throughout the several views.

In the drawing the two legs of the compass are indicated by A, and are substantially similar to each other, and are pivotally connected to the transverse pivot, or bolt B, which has a thumb nut 4, at one end, and a 65 head 5, at the opposite end. On one leg is a raised part 6, in contact with one flat side of the head, to prevent the pivot or bolt from turning, and shown in Fig. 9, of the drawing. The lower part of each leg extends 70 from a distance between the lower end of the flanges 7, and is integral therewith as shown in Figs. 7 and 8 of the drawing. The side flanges 7 of the legs A, extend about 75 three fourths of the length thereof and act as guides for the link members D. The sockets C, have spring splits as at 8, and are integral with the flanges, or plates 10. The lower parts of the leg members A, are pivotally connected at 9, to the flanges or plates 80 10. The split sockets C, are adapted to receive points, or marking elements, 12 and 13, which extend through the split-spring sockets and fasten therein by means of the spring splits 8, of the sockets C. One said 85 marking element or point 12, is eccentric, and has a manipulating seat 14, to rotate the point 12, and minutely set the same to desired place, after the compass is tightened, or set, by means of the thumb screw 4. The 90 opposite point or marking element 13, may be of steel, and removable, for the introduction of pencil, or pen, or other marking element. The upper pivotal ends of the legs A are widened out to receive the several 95 mechanical parts which form the compass, and on one inner side of each widened part of a leg A, is a round hub or projection 15, eccentric with the central pivot B, said hubs may be properly termed eccentrics 15.

D, are link members which have upper holes 16, to conform with the round inwardly projecting eccentrics 15 of the legs, and said links are adapted to slide easily between the flanges, or sides 7, that is in the U of the legs. 100 The holes 16 have opposite recesses, or slight indentations 17, in order that the wearing part of said holes shall be more marked on the inner sides than on the outer sides of the holes. The links have slots 18, and the 105 arm parts 19 of the links are shortened, to escape the lower extended parts of the legs D.

20 are transverse pins through the leg members A, and fit in the slots 18 in the link members D. The pins 20, are retaining pins, to retain the arms 19 of the links in position 5 in the U part of the legs A, consequently to afford spring tension to the lower end parts of the links which pivot, or connect to the pins E, of the flanges 10. The lower end parts of the link members have suitably 10 formed recesses F, to fit the pins E, and the pins 20 engage with the arms 19 of the links and retain the recesses F in spring tension contact with the pins E. The inner ends of the recesses F are slightly indented or 15 extended, as at 22, that the pins E may tend to wear on the ends of the recesses, instead of the lower and upper parts thereof.

The vertical handle H has a lower flat shank part I, having a vertical slot J, and 20 two horizontal slots K. The bolt or pivot B, passes easily through the slot J, and the slots K receive the studs S, of the legs A, to retain the handle H, that is, when the compass is extended, the studs S in the slots K 25 gradually lift the handle, and when the compass is contracted, said studs gradually lower the handle H, and retain the same, thereby preventing any lateral movement of the handle.

30 When the compass is being extended, the studs S, acting from opposite sides of the legs A, and in the slots K, slightly raise the handle H. At the same time the eccentrics 35 engage the holes 16, in the links D, thereby raising said links and consequently raising the pins E, together with the double flanges 10, on their pivots 9, and thereby bring the sockets C on said flanges to vertical position. When closing or contracting the compass, 40 the handle H is brought downwardly together with the link members D, and the sockets C, together with their points 12 and 13 are substantially parallel, and always remain so.

45 What I claim as my invention and desire to secure by Letters Patent, is:—

1. In a compass, a central transverse pivot, or bolt, legs of U cross section pivotally connected thereto, eccentrics on the in-

ner sides of the legs, marking elements pivotally connected to the opposite ends of the legs, link members on the eccentrics and the opposite end of the links loosely connected to the marking elements and means in the legs and the links to retain said link and marking element connection, intact. 50

2. In a compass, a central pivot, legs of U cross section pivotally connected thereto, eccentrics on the inner sides of the legs, sockets pivotally connected to the opposite 60 ends of the legs, link members connecting the eccentrics with the sockets, link pressure means in the legs, an eccentric point or marking element in the socket, or sockets, of one said leg, and means on the marking element 65 to adjust the same, and a marking element in the socket, or sockets, of the opposite leg.

3. In a compass, a central pivot, legs pivotally connected thereto, eccentrics on the legs, marking elements pivotally connected 70 to the opposite ends of the legs, link members loosely connecting the eccentrics and marking elements, studs inwardly extending from one side of the legs, link pressure means in the legs, a centrally located handle having a 75 vertical slot and horizontal slots, said vertical slot to permit motion on said central pivot and the horizontal slots adapted to receive said studs to retain the handle half way between the positions of the two legs. 80

4. In a compass, a central pivot or bolt, a thumb-nut, at one end and a head at the opposite end thereof, legs pivotally connected thereto, means on one said leg to retain the head, guide flanges on the legs, eccentrics on 85 the inner sides of the legs, marking members pivotally connected to the opposite ends of the legs, link members connecting the eccentrics and the marking members and adapted to slide between said guide flanges, means in 90 the legs and in the link members to afford spring tension to the connections of the link members and the marking element members. 95
